(57) CLAIM

The ornamental design for a flap for a bag, as shown and described.

DESCRIPTION

FIG. 1 is a front perspective view of the flap for a bag.

FIG. 2 is a front view thereof.

FIG. 3 is a first side view thereof.

FIG. 4 is a second side view thereof; and,

FIG. 5 is another front view thereof with the flap in an unlatched position.

The broken lines showing the bag are included for the purpose of illustrating environment and form no part of the claimed design.

1 Claim, 5 Drawing Sheets

FIG. 1

FIG. 2

FIG. 3

FIG. 4

FIG. 5
